UNITED STATES PATENT OFFICE.

SEVERI MOILANEN, OF SOUTH PARIS, MAINE.

DESIGN FOR A SKEE.

54,113.

Specification for Design.

Patented Nov. 4, 1919.

Application filed May 26, 1919. Serial No. 299,994. Term of patent 14 years.

To all whom it may concern:

Be it known that I, SEVERI MOILANEN, a citizen of Finland, residing at South Paris, in the county of Oxford and State of Maine, have invented a new, original, and ornamental Design for Skees, of which the following is a specification, reference being had to the accompanying drawing, forming part thereof.

The figure is a perspective view of a skee, showing my new design.

I claim:

The ornamental design for a skee, as shown.

SEVERI MOILANEN.

Witnesses:

ALTON C. WHEELER,
NORA A. DUNHAM.
